UNITED STATES PATENT OFFICE.

PERCY A. HORSWELL, OF CLEVELAND, OHIO, ASSIGNOR TO THE CAROLA COMPANY, OF CLEVELAND, OHIO, A CORPORATION OF OHIO.

DESIGN FOR A CABINET FOR TALKING-MACHINES.

49,519.

Specification for Design.

Patented Aug. 15, 1916.

Application filed March 15, 1916. Serial No. 84,499. Term of patent 7 years.

● *To all whom it may concern:*

Be it known that I, **PERCY A. HORSWELL**, a citizen of the United States, residing at Cleveland, in the county of Cuyahoga and State of Ohio, have invented a new, original, and ornamental Design for a Cabinet for Talking-Machines, of which the following is a specification, reference being had to the accompanying drawings, forming a part thereof.

In said drawings, Figure 1 is a perspec-

tive view of a cabinet for talking machines; Fig. 2 is a front view; and Fig. 3 is a side view, all figures showing my new design.

I claim:

The ornamental design for a cabinet for talking machines, substantially as shown.

PERCY A. HORSWELL.

Witnesses:

L. I. PORTER,
A. J. HUDSON.
